UNITED STATES PATENT OFFICE.

EDWARD A. SMITH, OF NEW YORK, N. Y.

SNOW-MELTING MACHINE.

1,300,035.

Specification of Letters Patent.

Patented Apr. 8, 1919.

Application filed September 25, 1916. Serial No. 121,935.

To all whom it may concern:

Be it known that I, EDWARD A. SMITH, a citizen of the United States, and resident of New York, in the county of New York and State of New York, have invented a certain new and useful Snow-Melting Machine, of which the following is a specification.

My invention relates to portable incinerators or snow melting machines.

10 An object of the invention is to provide a practical machine of the character stated, which may be self-propelled and is operative to collect the snow from the street as the machine advances, the snow being distributed 15 into an oven where it is melted as fast as it enters. Any unmelted snow is agitated by air and hot water obtained from the melted snow. The machine is thus operative as it travels along the street to collect and melt 20 the snow, the process being continuous.

The invention may consist of a self-propelled vehicle comprising a large tank for any suitable liquid fuel, such as oil or gasoline. As the machine advances, the snow 25 may be collected by a movable scoop at the front of the machine and thrown into the melting oven or fire box by suitable means such as a rapidly revolving wheel or propeller having blades by which the snow is 30 thrown rearwardly and scattered or diffused through the oven. Additional means is provided for agitating the snow, comprising slotted pipes in the bottoms of the fire box through which air under pressure is supplied from a blower or compressed air tank. 35 A series of atomizers may be provided within the oven for vaporizing the fuel supplied from the tank and mixing it with air supplied under pressure. The fuel thus intimately mixed with the air, burns with an intense heat which melts the snow as fast as it enters the fire box. The fuel in the tank is maintained under a continuous pressure by suitable means, such as a motor-driven 40 air compressor communicating with the tank. The fire box may be located beneath the forward portion of the fuel tank and close to the ground where the snow will enter it directly, without the necessity of 45 being elevated to any material extent. The fire box may have an inner lining of fire-proof material, and an outer casing, providing beneath the fire box a compartment in which the melted snow runs and from which 50 it is discharged. Also an air space is pro-

vided between the fire box and the fuel tank. Air under pressure may be supplied to the atomizers by a blower which may be run by an electric or other motor, the motor also serving to drive the propeller by which the 60 snow is thrown into the fire box.

Various other features and advantages will appear hereinafter.

In the accompanying drawings, Figure 1 is a sectional side elevation of a machine 65 constructed in accordance with the principles of my invention.

Fig. 2 is a front elevation of the machine.

Fig. 3 is a detail section of a connection for the vertical steering rod to the top of 70 the steering knuckles to which the forward wheels are attached.

Fig. 4 is a detail sectional elevation showing a portion of the fuel tank, supporting beams therefor, and a rod forming part of 75 the connections for operating the brakes.

Fig. 5 is a detail plan showing certain connections between the valve controlling lever and the valves and rheostat.

Fig. 6 is an elevational view of the atomizers and the air and fuel supply pipes and controlling valves therefor and spark plug.

Fig. 7 is a sectional view of an equalizing rod forming part of the steering apparatus.

Fig. 8 is a detail view showing valves controlling the supply of fuel and air to the atomizers, and a rheostat by which the motor which drives the blower or compressor is controlled.

Fig. 9 is a sectional elevation showing a 90 modified construction in which an endless conveyor is employed to carry the snow into the fire box.

Fig. 10 is a fragmentary view showing a 95 portion of the conveyor and its track.

The machine may comprise a tank 11 to contain crude oil, kerosene, gasoline or any other suitable liquid fuel, said tank being mounted on a truck having front and rear power driven wheels 12 and 13. The truck may comprise channel irons 14 extending along the sides of the tank, and cross-beams 15 beneath the tank. The fuel tank is of large capacity and extends about the full length of the machine.

The fire box or oven 16, in which the snow is melted, is located beneath the forward portion of the tank 11, being horizontally disposed with its floor or lower wall only a short distance above the level of the ground.

The front axle 17 instead of extending straight across the machine between the hubs of the wheels 12, is offset downwardly as shown in Figs. 1 and 2, to extend transversely beneath the fire box 16 and through the water compartment, said axle having upturned portions 17' at the ends of said transverse portion. The portions 17' extend upwardly into position to provide supports for the beams 14 of the truck by means of springs 14^a. It will be seen that with this arrangement the axle 17 is carried outside of the fire box, providing ample room for the latter without subjecting the axle to the internal heat of the fire box, and moreover providing a structure by which the floor of the fire box may be supported by the axle and by which the weight of the truck, and parts thereon, is directly supported by the axle.

The machine may be self-propelled by any suitable means as for example, small electric motors (not shown) mounted on or in the front and rear wheels 12, 13. The rear end of the truck is supported on springs 18 mounted on the rear axle 19. The brake mechanism may comprise brake arms 20 and 21, (Fig. 1) pivoted at 30, and adapted to be expanded into frictional engagement with the brake flange 31 by means of a cam or eccentric actuated by a rock arm 32. This is shown more particularly in Fig. 13, wherein the arm 32 is shown pivoted to the cross member 32^a and provided with a forwardly extending cam 32^b and a rearwardly extending cam 32^c. One of these engages with brake arm 20 and the other with brake arm 21. As arm 32 moves forward one moves upward and the other downward, thus pushing the shoe 20 upward and shoe 21 downward. Any other suitable form of brake might be employed. The brakes are controlled by a brake lever 33 near the driver's seat 34, said brake lever being connected through a rod 35 to an arm 36 (Figs. 1 and 4) the arm 36 being secured to a rock shaft 37 extending across the machine beneath the tank 11. Rock arms 38 on the shaft 37 are connected through rods 39 to the rock arms 32. Cushioning springs 40 (Fig. 1) may be mounted on the rods 39.

The steering mechanism may comprise a steering wheel 41 connected through suitable means, such as a worm and gear shown in dotted lines, to a rock shaft 41' having depending rock arms 42, each connected by a universal joint 43 to a stud 44 (Fig. 7) projecting from a tubular rod 45. Each rod 45 has connected thereto, a rock arm 46 attached at its outer end 47 to a vertical rock shaft 48. Each of the rods 48 is supported in a vertical position by a bracket 48' and extends downward and is operatively connected to steering hub 49. Cushioning springs 45' are provided in the hollow rods 45. The steering wheel 41 when rotated is

operative through the connections described to turn the front wheels for steering the machine.

The snow is collected by means of a scoop 50 inclined downwardly and forwardly from the front end of the fire box 16, and provided at intervals along its front edge with fingers or feelers 51. These feelers are normally supported a short distance above the surface of the street by skates or runners 54' and have their forward ends inclined upwardly so that if any obstruction on the street should be encountered the feelers 51 will be lifted upwardly and swing upwardly the forward portion of the scoop 52 or platform 50, which is hinged at 53 to permit such movement. Wheels 54 supported on a section 55 of the platform behind the hinged section 53, are normally held off the pavement, but may operate to support the platform 50 or lift it upwardly when said wheels encounter an elevation or obstruction in the road, thus moving the hood vertically. Located in front of the fire box and flaring outwardly therefrom is a hood 56 the lower side of which may consist of the scoop 50. The hood has at its front face a vertical screen 57 to thereby regulate depth of the intake opening 60 between said end 59 and the scoop 50 and throwing escaping heat down on the snow. The hood 56 is adapted to be lifted when not in use by any suitable means such as a sprocket chain 61 attached to the hood and extending over a sprocket wheel 62, rotatable by a hand-wheel 63 and held against backward rotation by a pawl and ratchet or other equivalent means. The hood may have slot-and-pin connections 61' with brackets at the front of the fire box, to limit the movement of the hood and hold it to the fire box.

The snow as it enters the hood through the opening 60 is thrown rearwardly by a rapidly revolving snow-wheel or propeller 64, comprising a series of blades 65 radiating from a hub 66. Fire-proof material 66^a surrounds the driving shaft 67 on which the snow-wheel is mounted, said fire-proof material serving to protect the shaft 67 and prevent overheating thereof. The wheel 64 may be mounted on the hood and adjustable up and down therewith if desired. The wheel 64 operates to throw the snow with considerable force well back into the fire box at the same time diffusing or spreading the snow so as to be brought into immediate contact with the heated air and walls of the fire box, and thus quickly melted. The snow may be further agitated by blowing air and hot water through the fire box by means of slotted pipes 67^a in the bottom of the fire box. The air under pressure may be supplied from a blower 97 or a separate blower or compressed air tank communicating through pipes 67^b with the pipes 67^a. The snow-

wheel 64 may be driven by any suitable means. As here shown, it is driven by an electric motor 68 connected thereto through a sprocket chain 69 running over sprocket 5 wheels on the motor and snow-wheel, and intermediate guiding sprockets 70 and 71. The motor 68 may be mounted in a housing or compartment 72, which also provides a receptacle for storage batteries 73 from 10 which power may be supplied for running the motor 68 and truck motors.

The fire box 16 may have an inner lining 74 composed of fire bricks or other suitable fire-proof material, having a backing 75 of 15 sheet material. The fire box may be connected to the lower surface of the tank 11 by means of bolts 76, the fire box being spaced from the tank to provide an air chamber or passage 77. Beneath the floor 20 of the fire box is a spaced air and water compartment 78 provided by a sheet metal casting 79 secured as by means of bolts 80 to the bottom of the fire box.

The fire bricks 74 which form the floor 25 of the fire box may be spaced to provide slots 80 through which the water produced by the melting snow runs into the compartment 78. A wider opening 81 may also lead from the fire box into the compartment 78. Outlet 30 openings 82 and 83 permit the water from the compartment 78 to be discharged. If the machine is going uphill, the fire box being tilted upwardly, the water is discharged principally through the opening 83, while 35 if the machine is going down hill, the discharge will be mainly through the front outlet 82. One purpose of running the water through the compartment 78 is to prevent injury to the pavement by heat from the fire box, particularly when standing still. The water at a high temperature being discharged on the pavement from the water compartment serves to melt any remaining snow on the street.

40 The oil or other liquid fuel may be supplied to the tank 11 at an intake 85. The oil in the tank is normally maintained under pressure provided by any suitable means, as for example, a rotary compressor 86 driven by an electric or other motor 87. The air may be drawn into the compressor through a suction pipe 88 and strainers 89 and forced under pressure through the pipe 90 into the tank. The pressure gage 91 indicates the pressure in the tank, while a relief valve 92 operates automatically to permit the air to discharge through a pipe 93 when the pressure exceeds a predetermined limit.

45 The fuel under pressure is conveyed from the tank through pipes 94 and 95 (Figs. 1, 6 and 8) to a series of atomizers 96. By reference to Fig. 6 it will be observed that each of the supply pipes 95 supplies fuel for 3 of the atomizers. Air under pressure is supplied to the atomizers by a blower 97. The

blower may be driven by a belt 98 from the motor 68. The compressed air is conveyed through pipes 99 and 100 (Figs. 1, 6 and 8) to the atomizers, where it is mixed with incoming fuel in a manner well understood by 70 those skilled in the art. The supply of fuel to the individual atomizers is controlled by valves 101, so that any one or more of the atomizers may be cut out as may be desired. The vaporized fuel may be ignited by means 75 of spark plugs 102 (Fig. 1), each atomizer normally supplying a continuous flame.

Referring to Fig. 8, the supply of fuel through the pipe 94 to the atomizers may be controlled by a valve 103. The supply of 80 air to the atomizers may also be controlled by a valve 104 in the pipe 99. The valves 103 and 104 may be actuated by the valve controlling lever 105 pivoted at 106 and connected through a rod 107 extending rearwardly therefrom of a lever 108 (Fig. 5) pivoted at 109 and connected through a link 110 to levers 111 and 112 (Fig. 8) the latter connected to the valves 103 and 104 respectively. The link 110 may also be connected to 90 a rheostat arm 113 for controlling the speed of the motor 68. It will thus be seen that the valve-regulating lever 105 is operable to simultaneously reduce or regulate the supply of fuel and the supply of air to the atomizers, and the speed of the motor. It will be understood that if desired, the speed of the motor may be controlled entirely independently of the supply of fuel to the atomizers. Also the supply of fuel and the supply of 95 air to the atomizers may be separately controlled if desired.

A cab 115 may contain the driver's seat 34 and the various controlling devices, such as the steering wheel 40, brake lever 33, 105 valve-regulating lever 105 etc., all within convenient reach of the driver. A controller 116 may be located in the cab for controlling the traction motors for the wheels 12 and 13. The compartment 117 beneath the 110 driver's seat forms a convenient receptacle for storage batteries for running the traction motors and the motor 87, or supplying electric current for other purposes as may be desirable. The fire box is preferably provided with a door or removable section 16 adjacent the atomizers.

In Figs. 9 and 10, is shown a modification in which an endless conveyer 118 is used for conveying the snow into the fire 120 box 16. Said conveyer may be driven by endless sprocket chains 119 running over sprocket wheels 120 and 121, said chains carrying a series of transverse slats 122 by which the snow is collected and carried rearwardly into the fire box. Springs 123 hold said slats in their normal position and swing them into position as they ride around the front end of the conveyer. The slats 122 carry rollers 124 which run on tracks 125. 125

The conveyer may be driven by a belt or chain 126 extending rearwardly to and driven by the motor 68 or other source of power.

5 Various modifications other than those herein mentioned may be resorted to within the spirit and scope of my invention, and some parts of the invention may be used without others.

10 What I claim as new and desire to secure by Letters Patent of the United States is:

1. In a snow melting machine, the combination with a truck, of a fuel tank mounted thereon, a fire box, means for scooping up the snow, a snow wheel for throwing the snow into the fire box, a motor, means between the motor and said wheel for driving the latter, atomizers, means for conveying fuel from the tank to the atomizers, 15 and a blower operated by said motor to supply air under pressure to the atomizers, valves respectively controlling the supply of fuel and the supply of air to the atomizers, a lever connected to regulate said 20 valves, a rheostat to control the speed of the motor, and connections from said lever to the rheostat, whereby the speed of the motor and the supply of fuel and compressed air are concomitantly controlled by 25 the actuation of said lever.

2. In a snow melting machine, the combination with a truck, of propelling means therefor, a receptacle open at its forward end to receive the snow, a hood at said open 35 end of the receptacle, a scoop by which the snow is collected and over which it is conveyed through the hood to said receptacle, a shutter or screen for partially closing the front of said hood and deflecting the heated 40 air, and means for adjusting said screen to regulate the width of the opening through which the snow enters said hood, said hood and scoop shiftable up and down, and wheels carried by said scoop normally out 45 of contact with the ground and adapted to lift the hood when an obstruction or elevation in the road is encountered.

3. In a snow melting machine, the combination of a snow-melting fire box open 50 only at its forward end, means for delivering the snow into said fire box, fuel atomizers at the rear of said fire box positioned so as to direct a flame forwardly through said fire box, a multiplicity of air blast 55 openings in the bottom of said fire box for directing compressed air upwardly through

the snow in a direction substantially at right angles to the direction of said flame, and means for supplying compressed air to said openings.

60

4. In a snow melting machine, the combination of a snow-melting fire box open only at its forward end, a rotatable snow wheel at the open end of said fire box for throwing the incoming snow backward in 65 said fire box, a hood and scoop extending forward from said fire box in advance of said snow wheel, a movable screen carried by said hood in advance of said snow wheel, means for supplying heat to said fire box, 70 and means for conducting the snow water from said fire box.

5. In a snow melting machine, the combination of an elongated snow-melting fire box open at its forward end; a scoop, hood 75 and screen for controlling the collection and supply of snow to said fire box; fuel atomizers at the rear of said fire box for directing a flame forwardly in said fire box; a snow wheel in the forward end of said fire 80 box having blades for engaging the snow supplied by the hood, scoop and screen and throwing it rearwardly in said fire box; and fire-proofing material lining said fire box and covering the shaft of said snow 85 wheel.

6. In a snow melting machine, the combination of an elongated open ended fire box, means for delivering the snow to said fire box, a fireproof lining in said fire box, 90 openings through said lining and fire box for draining off the snow water, a compartment beneath said fire box for collecting the water received from said fire box, a suitable outlet for said chamber, an air supply 95 pipe extending beneath said fire box and terminating in a number of outlets extending through said fire box and its lining and terminating close to said openings through which the water is drained from the fire 100 box, means for heating said fire box by a flame within said box, and means for supplying air under pressure to said supply pipe, whereby snow and water are thrown upwardly into the flame.

105

Signed at New York in the county of New York and State of New York this 22nd day of September A. D. 1916.
